(57) **CLAIM**

The ornamental design for a suspension link for a vehicle, as shown and described.

DESCRIPTION

FIG. 1 is a perspective view of a suspension link for a vehicle according to a first representative embodiment of our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view of a suspension link for a vehicle according to a second representative embodiment of our new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a left side elevational view thereof; and,

FIG. 14 is a right side elevational view thereof.

The broken lines in the drawings show portions of the suspension link for a vehicle that form no part of the claimed design.

1 Claim, 6 Drawing Sheets
